[57] CLAIM

The ornamental design for a keyboard and adjustable display, as shown and described.

DESCRIPTION

FIG. 1 is a front and right perspective view of a keyboard and adjustable display, with the display in the raised position, showing our new design;
FIG. 2 is a front and right perspective view, with the display in the lowered position, thereof;
FIG. 3 is a right side elevational view thereof;
FIG. 4 is a left side elevational view thereof;
FIG. 5 is a front elevational view thereof;
FIG. 6 is a rear elevational view thereof;
FIG. 7 is a bottom plan view thereof; and,
FIG. 8 is a top plan view thereof. In FIGS. 3 through 8, the display is shown in the raised position.
